United States Patent Office

Des. 176,918
Patented Feb. 14, 1956

176,918

FOUNTAIN HEAD UNIT

Clare E. Hodgman, Mamaroneck, N. Y.

Application June 21, 1955, Serial No. 36,612

Term of patent 3½ years

(Cl. D2—3)

FIG. 1.

FIG. 2.

FIG. 3.

FIG. 4.

Fig. 1 is a view in perspective from the operating side of a fountain head unit embodying my new design;

Fig. 2 is a top view of the unit of Fig. 1;

Fig. 3 is a front view of said unit; and

Fig. 4 is a side view thereof.

I claim:

The ornamental design for a fountain head unit, as shown.
